United States Patent Office

Des. 227,409
Patented June 19, 1973

227,409

MOTION PICTURE CAMERA HOUSING

Walter H. Bach, 1771 N. Crescent Heights Blvd.,
Los Angeles, Calif. 90069

Continuation of design applications Ser. No. 25,132 and
Ser. No. 25,133, both Sept. 22, 1970. This application
Dec. 20, 1971, Ser. No. 210,310

Term of patent 14 years

Int. Cl. D16—01

U.S. Cl. D61—1 C

FIG. 1

FIG. 3

FIG. 2

FIG. 4

FIG. 5

FIG. 6

FIG. 8

FIG. 7

FIG. 9

FIG. 10

FIG. 1 is a front perspective view of a motion picture camera housing showing my new design;

FIG. 2 is a right side elevational view thereof;

FIG. 3 (remains the same);

FIG. 4 (remains the same);

FIG. 5 is a bottom plan view thereof;

FIG. 6 is a front perspective view of another embodiment of my new design;

FIG. 7 is a right side elevational view thereof;

FIG. 8 is a front elevational view thereof;

FIG. 9 is a rear elevational view thereof;

FIG. 10 is a bottom plan view thereof.

This application is a continuation of D. 25,132 and D. 25,133, both filed Sept. 22, 1970, and now abandoned.

I claim:

The ornamental design for a motion picture camera housing, as shown and described.
